UNITED STATES PATENT OFFICE.

LESTER RAUH, OF NEW YORK, N. Y.

BATHING-SUIT.

1,213,257.

Specification of Letters Patent. Patented Jan. 23, 1917.

Application filed June 3, 1915. Serial No. 31,915.

To all whom it may concern:

Be it known that I, LESTER RAUH, citizen of the United States, residing in the borough of Manhattan, city, county, and State 5 of New York, have invented certain new and useful Improvements in Bathing-Suits, of which the following is a specification.

The present invention relates to improvements in bathing suits.

10 It is my object to make a bathing garment which will possess both the advantages of a two and a one piece suit and yet be produced very economically.

The invention consists in the novel features of construction hereinafter set forth and pointed out in the claims.

In the accompanying drawings: Figure 1 is a front view of the entire garment; Fig. 2 is a side view of the entire garment; Fig. 20 3 is a detail of the upper or shirt portion, and Fig. 4 is a detail of the lower or trunk portion.

In these drawings a shirt or jersey 1 has the usual openings 2, 2, for the arms, and 3 for the neck, shoulder straps 4, 4, also being provided. The left hand strap 4' is formed in two parts *a* and *b*, buttoned or otherwise fastened together. Sleeves may be provided if desired. I take this jersey 1 of 30 substantially ordinary form widened at the bottom and fit to it a trunk portion 6, shown in detail in Fig. 4. This trunk portion is inserted within the lower end of the body and stitched or otherwise secured to the body, 35 the lines of stitching being shown at 7, 7, on each side, at the top of the leg portions and the upwardly extending central sections 8, 8, of the trunk are stitched as at 9, 9, to the front and rear of the body. The trunk 40 portion may be made in any suitable manner. Great freedom is provided in this arrangement of body and trunk and a minimum of material required, thus lessening

the weight of the garment when in the water by reducing the amount of water absorbing material.

I claim:

1. A bathing suit comprising a shirt element and a trunk element, said trunk element having inverted U-shape upward extensions and U-shape recesses therebetween.

2. A bathing suit comprising a shirt element and a trunk element, said trunk element having portions of its upper part terminating in different horizontal planes to 55 permit freedom of the swimmer's legs.

3. A bathing suit comprising a shirt element and a trunk element, said trunk element having inverted U-shape upward extensions and U-shape recesses therebetween, 60 the top of said extensions and the bottom of said recesses being stitched to said skirt portion, said stitching being overlapped to prevent rising of the skirt around the swimmer's body.

4. A bathing suit comprising a shirt element and a trunk element, said trunk element being secured to said body element by intermittent stitching in different horizontal planes to permit freedom of the swimmer's legs and to prevent rising of the skirt around the swimmer's body.

5. A bathing suit comprising a body element and a trunk element, said trunk element being secured to said body element by 75 interrupted staggered stitching in different horizontal planes to permit freedom of the swimmer's legs and to prevent rising of the skirt around the swimmer's body.

In testimony whereof, I affix my signature in presence of two witnesses.

LESTER RAUH.
